CLAIM

The ornamental design for a vehicle jack, as shown and described.

DESCRIPTION

FIG. 1 is a front perspective view of a vehicle jack;
FIG. 2 is a front view thereof;
FIG. 3 is a back view thereof;
FIG. 4 is a right view thereof, the left side being a mirror image;
FIG. 5 is a top view thereof; and,
FIG. 6 is a bottom view thereof.
All broken lines represent unclaimed features of the article to which the design is applied.
